SLUG CASTING MACHINE

William L. Petersen, Springfield, N. Y., assignor
to Mergenthaler Linotype Company, a corpora-
tion of New York

Application December 18, 1935, Serial No. 54,986

20 Claims. (Cl. 199—61)

This invention relates to slug casting machines of the general organization disclosed in U. S. Letters Patent No. 1,980,110 to A. J. Stouges, wherein a line of matrices supported in a vertically movable line transporter or first elevator is presented to a mold, the mold filled with molten metal to form a slug or linotype against the matrices which produce the type characters thereon, and the mold thereafter brought into a position wherein the slug by the forward movement of an ejector blade, is ejected from the mold and dropped into a chute or guideway leading to a galley at the front of the machine.

Ordinarily the slug upon ejection from the mold is pushed between a pair of guiding surfaces spaced apart a distance equivalent to the thickness or point size of the slug and which serve to direct the slug properly into the chute leading to the galley. When slugs of large point sizes are cast, especially those having overhanging faces (T-shaped or L-shaped in cross section), the action of the ejector blade on the shanks of such slugs as they are pushed between the guiding surfaces, may have a tendency to tilt or cant them because of the relatively thin character bearing portions of the slugs capable of cooperating with the guiding surfaces, with the result that the slugs may drop into the chute leading to the galley inaccurately.

According to the present improvements, the guiding surfaces are dispensed with and, in order to insure that the slug is properly located for delivery to the chute, a device in the form of a buffer plate is presented in front of the mold when the latter is in the slug ejecting position and, as the ejector blade moves forwardly to eject the slug from the mold, the buffer plate engages the face of the slug and is held yieldingly thereagainst until the slug is fully ejected, whereupon the buffer plate is locked in its retracted position. When the ejector blade recedes, the slug is released, allowing it to drop into the chute for delivery to the galley. With an arrangement of this kind, it is apparent that, regardless of the kind of slug cast (the machine here being equipped to cast slugs with overhanging faces, T-shaped or L-shaped in cross section, as well as those without overhanging faces, as for instance recessed slugs formed with transverse ribs beneath the character bearing portion of the slug which render them self-supporting and plain slugs of the usual kind), the buffer plate will cooperate with the ejector blade to hold the slug firmly until it registers with the upper end of the chute.

Because of the different kinds of slugs adapted to be cast in the machine, the chute leading to the galley is equipped with relatively movable side walls adjustable to accommodate the slugs of different kinds. The side walls are sufficiently low so that, in the case of slugs with overhanging faces, they may extend beneath such faces and in close proximity to the shanks thereof and thus act to guide the slugs to the galley. When plain or recessed slugs are cast, the spacing of the chute walls is such as to accommodate the full width of the slugs.

The relative movement of the side walls of the chute is effected by an adjustment of the right hand wall, the wall at the left being fixed. When the parts are in normal position, the buffer plate is held in a retracted position away from the mold and the movable guide wall in a position spaced from the fixed guide wall a distance sufficient to accommodate overhanging slugs having shanks of normal size (usually about ten points). As the first elevator or line transporter descends, the movable wall is moved away from the fixed wall to a distance somewhat greater than that sufficient to accommodate slugs of the largest body sizes. At the same time, the buffer plate is tripped and allowed to move inwardly toward the mold into a position for engagement with the face of the slug before the latter is fully ejected from the mold. When the parts have assumed these positions, the movable wall of the chute will be held in its outermost position by the buffer plate.

After the slug has been cast and the mold moved to the slug ejecting position, ejection of the slug follows, this operation being effected by the ejector blade which engages the shank of the slug at its bottom edge, pushing it against the buffer plate which yields against spring action as the slug is ejected, the flat face of the buffer plate and the pressure exerted thereby on the slug being sufficient to hold the slug against tilting. When the buffer plate has yielded through a short distance, it trips the adjustable chute wall, which thereupon is moved, likewise under spring action, toward the fixed wall until it is arrested by the mold cap or a plate fixed to the mold cap, in one position or another depending upon the kind of slug being cast. Thus for T-shaped or L-shaped slugs having thin shanks and overhanging faces, the adjustable wall will be allowed to come in its full distance and extend beneath the overhanging portions of the slugs, no plate in this instance being provided on the mold cap. For slugs of other kinds, as for instance those of the recessed character, the plates provided on the

mold cap vary according to the size of the slugs, i. e., the plates are larger according as the slugs increase in size, so that the space between the fixed and the movable chute walls will always be 5 sufficient to accommodate the slug cast.

Referring to the drawings:

Fig. 1 is a front elevation of a portion of a slug casting machine equipped with the present improvements;

10 Fig. 2 is a side elevation of a portion of the machine shown in Fig. 1, and showing the parts in the position they will assume immediately after the ejection of the slug;

15 Fig. 3 is a front elevation of a portion of the machine shown in Fig. 1, and showing the first elevator in its lowermost position, with the parts set to receive the slug as it is ejected;

20 Fig. 4 is a perspective view of the buffer plate and a portion of the chute walls, looking at the parts from the rear, and showing them in the position they will assume just prior to the ejection of the slug and with the movable chute wall held in its outermost position by the buffer plate;

25 Fig. 5 is a horizontal sectional view of the buffer plate and the movable chute wall retaining plate, and showing the parts in their normal position;

30 Fig. 6 is a view similar to Fig. 5, with the parts in the positions they will assume just prior to the ejection of the slug, and with the buffer plate in its innermost position cooperating with the chute wall retaining plate to hold the latter in its position of maximum separation;

35 Fig. 7 is a view similar to Fig. 5, showing the parts in the positions they will assume just after the ejection of the slug, the slug shown being one with transverse supporting ribs;

40 Fig. 8 is a view similar to Fig. 7, some of the operating parts however being omitted, and showing the use of a smaller plate on the mold cap to accommodate a slug of smaller body size;

45 Fig. 9 is a view similar to Fig. 8, but showing the relation of the parts when a slug T-shaped in cross section is cast;

50 Fig. 10 is a perspective sectional view through the chute walls and illustrating the spacing thereof for a slug of large body size and which is equipped with transverse supporting ribs; and

55 Fig. 11 is a perspective sectional view through the chute walls and illustrating the spacing thereof when a T-shaped slug is cast.

In the operation of the machine, the matrices are first composed in line and transferred to a line transporter or first elevator A which thereupon descends to present the composed line to the face of a mold B previously located in casting position by a one-quarter rotation of a mold disc C on which the mold is mounted. Thereupon the mold, by a forward movement of the mold disc is 60 brought into contact with the composed line, the mold filled with molten metal to form a slug or linotype against the matrices which produce the type characters thereon, and the mold thereafter, by a three-quarter rotation of the mold disc, brought into a slug ejecting position, wherein an ejector blade D, movable in a fore-and-aft direction and positioned at the rear of the mold disc, comes forward into contact with the slug at base 65 of its shank, causing the slug to be ejected out of the mold, whereupon it is dropped into a chute E leading to a galley F arranged at the front of the machine and in which the slugs are stored, the first elevator in the meantime ascending to its uppermost or normal position.

Machines of this character are usually equipped to handle slugs of different kinds. Thus in Figs. 7 and 10, there is shown a so-called "recessed" slug X having its face or character bearing portion x supported by transverse ribs x¹ arranged beneath the face portion and adjacent the shank x², while in Figs. 9 and 11 there is shown a slug Y, T-shaped in cross section, with a large overhanging face y and a shank y¹. Another kind of slug (not shown but well known) is like the slug Y but of L-shape in cross section, and still another kind is the familiar plain or solid slug.

In order that the chute E leading to the galley may accommodate the different kinds of slugs, and guide them properly to the galley, one of the side walls of the chute is made movable and is adapted to be automatically adjusted according to the kind of slug being cast. As shown in the drawings (Figs. 10 and 11), the chute E includes in part a fixed base portion E¹ extending downwardly from the lower end of the mold (when the latter is in slug ejecting position) and curving forwardly to the galley F, a left side wall E² formed integral with the base portion and which is provided at its upper edge with a laterally extending flange E³. This fixed portion of the chute is held in place by a lug e projecting forwardly from the flange portion E² near the upper end of the chute and screwed to the usual vise frame G of the machine (see Figs. 4 and 7).

30 The chute also includes a movable right hand portion E⁴ having a vertical wall member E⁵ curved to fit the base portion E¹ of the chute and adapted, together with such base portion and the fixed side wall E², to form a guideway through which the slugs pass as they travel to the galley. The vertical wall member E⁵ is likewise formed at its upper edge with a flange E⁶ extending laterally from said wall member in a direction opposite to that of the flange E³ but at the same level as the latter. When a T-shaped slug (such as the slug Y in Fig. 11) is cast, the side wall members E² and E⁵ of the chute are positioned in closely spaced relation to accommodate the thin shank portion y¹ of the slug and the flanges E³ and E⁶ 45 extend beneath the overhanging face portion y of the slug, whereby the slug will be supported in an upright position and guided accurately into the galley. An L-shaped slug is handled in the same way except that in such case only one of the flanges E³ or E⁶ will extend beneath the overhanging face of the slug. However, for a recessed slug (such as the slug X in Fig. 10), due to the presence of the ribs x¹, the side walls E² and E⁵ are spaced apart a distance corresponding 50 to the full width of the slug face, and the slug is delivered to the galley solely under the guiding influence of these side walls E² and E⁵ (the flanges E³ and E⁶ not being required for that kind of slug). The same holds true in the case of a plain 55 or solid slug which presents no overhanging face. The spacing of the chute walls E² and E⁵ depends entirely upon the kind of slug cast and is controlled automatically in accordance with a predetermined setting, as will presently be described.

In order that the right hand wall member E⁴ may be located in its different positions of adjustment, it is mounted on a slide H arranged for limited movement crosswise of the machine in a horizontal portion J of a bracket J¹ screwed to the vise frame, and wherein the slide is held by a tongue and grooved connection H¹. The means for securing the member E⁴ to the slide H includes a reinforcing piece comprising a laterally extending flange E⁷ formed at the outer edge of the 75

flange member E^6 for a portion of its length (see Fig. 2), and a vertical flange member E^8 likewise formed at the outer edge of the flange E^6 and which terminates at its upper end in a flat ear E^9 .

5. screwed to the slide H .

Normally, the slide H (and consequently the movable side member E^4 of the chute) is held in its leftmost position by a spring H^2 secured at one end to a pin H^3 projecting upwardly from the 10 tongued portion of the slide H and anchored at its opposite end to a pin H^4 extending transversely through the horizontal portion J of the bracket J^1 , said horizontal portion being formed with a recess J^6 at the top and near its right end to provide 15 clearance for the pin H^3 and spring H^2 during the movement of the slide (see Figs. 1, 3, 6 and 7). However, near the beginning of a machine cycle of operation, the slide H is moved to its extreme 20 rightmost position where it is held pending the ejection of the slug, by a buffer plate K formed with a flange K^1 , which engages at the left of a vertical plate H^5 secured to the slide H (see Figs. 4 and 6).

The purpose of the buffer plate K just alluded 25 to, is to hold the slug against tilting or canting so that it may be positioned properly for entry into the chute. It is arranged opposite the mold in the slug ejecting position thereof, is as long as the mold itself and wide enough to accommodate 30 slugs of the largest point sizes. This buffer plate has secured to it, a flat padding strip K^2 so as not to damage the faces of the slugs, and is carried at the inner end of a slidable member K^3 arranged for limited fore-and-aft movement in 35 another horizontal portion J^2 of the bracket J^1 and which extends at right angles to the portion J that supports the slide H . The slide K^3 is tongued and grooved, as at K^4 , in the bracket J^1 and is urged inwardly toward the mold by 40 a compression spring K^5 housed in a longitudinal recess K^6 formed in the right side wall of the slide K and which is confined at its ends between the buffer plate K and a small plate K^7 fastened to the front end of the horizontal fore-and-aft portion J^2 of the bracket member J^1 and formed 45 with a tongue projecting into the longitudinal recess K^6 that houses the spring K^5 (see Figs. 1 and 7). In the normal position of the parts, the buffer plate slide K^3 is spaced somewhat away from the mold (see Fig. 5), in which position it is held 50 by an eccentric K^8 fixed at the lower end of a vertical pin extending through a bearing lug J^3 formed on the bracket J , and which pin at its upper end, has fixed thereto an arm K^9 urged 55 in a direction to wedge the eccentric K^8 against the slide K^3 by a spring K^{10} that presses against the front edge of the arm K^9 and which seats in a lug J^4 formed on the bracket J^1 .

Now, when the machine cycle of operations is 60 inaugurated, the slide H carrying the movable chute wall is moved from its leftmost position (Fig. 5) to its rightmost position (Fig. 6), wherein the chute walls have their maximum degree of separation which, as previously stated, is 65 slightly more than that necessary to accommodate the largest slug that the machine will cast. As the slide nears its rightmost position, a pin H^6 fixed therein and which extends forwardly through a slot formed in the horizontal portion 70 J of the bracket J^1 engages at its outer end against a cam surface K^{11} formed at the end of the arm K^9 that operates the eccentric K^8 , causing said arm to pivot against the action of the spring K^{10} , thereby turning the eccentric and 75 releasing the buffer slide K , whereupon the latter

moves inwardly toward the mold under the action of its associated spring K^5 until arrested by a block K^{12} screwed at the front end of the slide and banking against the supporting bracket J^1 at the front end of its horizontal portion J^2 (see Fig. 6). When the buffer plate is in its innermost position, the flange K^1 thereon engages at the left of the vertical plate H^5 carried by the slide H (see Figs. 2 and 4), thus locking said slide in its rightmost position, all as previously described.

The means for effecting the movement of the slide H to the right includes a lever L pivotally connected at its upper end to the vise cap and which at its lower end is bent inwardly (see Figs. 15 1 and 2) to engage at the left of the pin H^6 projecting from said slide. As the first elevator 20 A starts to descend to present the line of matrices to the mold, an edge cam A^1 fastened thereon engages a cam follower L^1 carried at the end of an arm L^2 fastened to the lever L , causing the latter to swing in a counterclockwise direction and, through its engagement with the pin H^6 , effecting the movement of the slide member H to its rightmost position as previously mentioned, 25 where it is held by the buffer plate K ; it being understood that the cam A^1 on the first elevator is sufficiently long to hold the slide H in its rightmost position until the buffer plate has had an opportunity to reach its rearmost position.

Although the lever L and the arm L^2 fastened thereto act as a unit, actually they are formed in two parts to permit of slight angular adjustment when required, the devices for this purpose including a set screw l threaded through a lug l^1 formed on the lever and banking against the arm L^2 at the end l^2 thereof opposite the cam follower L . It might also be stated here that the pin H^6 through which the slide H is actuated to the right is provided at its outer end with a 40 round-headed screw h that bears against the cam surface K^{11} of the arm K^9 and which is threaded into the end of the pin likewise to permit slight adjustments when required.

After the casting operation, the mold disc C 45 is moved through three-quarters of a rotation to bring the mold B into the slug ejecting position, the first elevator meanwhile ascending to its uppermost position, but this latter movement of the elevator will have no effect upon the slide H 50 and consequently the movable side wall of the chute, since, as previously stated, the slide H is held in its rightmost position by the buffer plate K .

When the mold has reached the slug ejecting 55 position, the mold disc comes forward as usual to a position where its front face is in line with or positioned slightly to the front of the chute leading to the galley (see Figs. 2 and 7); and immediately after the mold disc starts its forward 60 movement, the ejector blade D likewise moves forward through the mold slot and engages the rear or bottom edge of the slug. The continued forward movement of the ejector blade effects the ejection of the slug from the mold, but before 65 the slug clears the mold, the front face thereof engages the buffer plate K and, as the latter is held yieldingly against the slug, the slug is prevented from canting or tilting as it leaves the mold. The buffer plate continues to yield against 70 the action of the spring K^5 until it reaches its outermost or forward position (see Fig. 7), at which time the slug will be entirely clear of the mold, the slide H in the meantime having been released when the buffer plate K moves out of the 75

way of the plate H^5 carried by the slide. The slide H , immediately upon its release, moves to the left under the action of the tension spring H^2 associated therewith and, in so doing, releases the arm $5 K^9$, which thereupon is free to effect the locking of the buffer plate slide K^3 in its forward position.

As the chief function of the slide H is to position the movable side wall of the chute leading to the galley to accommodate slugs of different 10 kinds, the distance through which it moves to the left will vary in accordance with the slug being cast. Accordingly, the slide H is arrested, in its movement to the left, in different positions, as determined by the banking of a pin H^7 associated 15 with said slide against a plate b screwed to the mold cap or against the upper edge of the mold cap itself.

The pin H^7 extends in a fore-and-aft direction and is mounted in a boss H^8 formed in the slide H 20 and yieldingly held in close spaced relation with the mold disc (when the latter is in its forward position during the ejection of the slug) by a spring H^9 encircling an inner reduced end of the pin and confined between the outer large portion 25 of the pin and a shoulder presented by a wall H^{10} in the hole drilled in the boss to receive the pin (see Fig. 5). The inner reduced end of the pin H^7 extends through the wall just mentioned and is provided with a nut H^{11} threaded on the end 30 of the pin and a washer H^{12} that banks against said wall at the face thereof opposite that against which the spring banks, thus limiting the movement of the pin toward the mold disc. The pin H^7 is yieldingly mounted for safety and to prevent 35 damage to the parts in the event the mold disc is pulled forward by hand for any reason.

The distance through which the slide H carrying the right hand wall of the chute is adjusted to the left is varied according to the kind of slug being cast, and such variations are effected by using 40 plates b of different sizes on the mold cap. Thus, as shown in Fig. 7, where the slug is of the recessed variety, the plate b is large, and accordingly the spacing between the side walls of the chute will 45 be correspondingly large to accommodate slugs of this size. For slugs of the same kind but of a smaller point size, the plate is correspondingly smaller as shown in Fig. 8. For overhanging slugs, like the T-shaped slug shown in Fig. 9, no plate 50 need be employed and in such instances, the pin H^7 may bank directly against the mold cap or the chute wall be allowed to return to its original position as determined by the engagement of the lever L with the stop pin j . Under such conditions, the plate H^5 passes behind the overhanging 55 face of the slug and the right hand wall E^5 of the chute will be located in its innermost position wherein the distance between the two walls E^2 and E^5 will be sufficient merely to accommodate the 60 thin shank of the slug.

With the walls thus adjusted properly to receive the slug, the latter, as the ejector blade recedes, is released and thereupon drops into the chute for delivery to the galley. In this connection, it may be noted that the flanges E^3 and E^6 65 curve inwardly at their upper ends toward the base E^1 of the chute (see Figs. 2 and 3) in order to insure that slugs with overhanging faces will pass properly into the chute when released by the 70 ejector blade.

After ejection of the slug and delivery thereof to the galley, the mold disc recedes, withdrawing the plate b on the mold or the mold itself, as the case may be, out of the path of the pin H^7 75 carried by the slide H , whereupon the latter,

under the influence of its associated spring H^2 , will be returned to its extreme leftmost position, which is determined by an adjustable banking screw j , against which the slide actuating lever L at its lower end abuts. With the buffer plate K locked in its forward position and the right hand guide wall in its leftmost position, the parts are again normal and ready to be reset during the casting of the next slug.

As a precautionary measure, in the event the buffer plate is not actuated to its innermost position, wherein it holds the slide H against movement to the left during casting and prior to the ejection of the slug, which might result in damage to the parts, a safety device is provided in 10 the form of a yieldable pin M horizontally arranged in a boss J^5 carried by the supporting bracket J^1 and in line with the cam A^1 carried by the line transporter. The pin M (Fig. 5) is formed with a collar M^1 , spring-pressed against 15 a pin M^2 extending radially through the boss and which determines the outermost or normal position of the pin M . When the first elevator descends to position the parts, as previously described, it will engage the pin M , pushing it to the right and, if the parts have been properly set, said pin will enter a recess k formed in the bottom edge of the buffer carrying slide K^3 , and which will be brought into registry with the pin 20 when the slide is in its rearward position. In such circumstances, the pin M will have no effect, since prior to the time that the slug is ejected from the mold, the first elevator will have ascended to its uppermost position, allowing the pin, under the influence of its spring, 25 to be withdrawn from the recess k , thus freeing the slide K^3 and allowing it to move forwardly, in the manner described, when the slug is ejected. However, in the event the buffer plate has 30 not been properly located in its rearward position during the initial phases of the machine cycle, the recess k will not register with the pin M and the latter will bank against the slide K^3 . The pin M , therefore, will not yield as the first 35 elevator A descends, but rather will act to arrest 40 the elevator before it reaches its lowermost position, in which event the customary vise automatic 45 will act to stop the machine.

In the accompanying drawings, the invention 50 has been shown merely by way of example and in preferred form, and obviously many variations and modifications may be made therein which will still be comprised within its spirit. It is to be understood, therefore, that the invention is not limited to any specific form or embodiment, 55 except insofar as such limitations are specified in the appended claims.

Having thus described my invention, what I claim is:

1. In a slug casting machine, the combination 60 of a mold, means for ejecting the cast slug from the mold, a guide into which the ejected slug passes, said guide including a wall settable to accommodate slugs of different sizes, and means acting automatically to move the wall to a predetermined setting as the slug is being ejected from the mold.

2. In a slug casting machine, the combination 65 of means for casting slugs of different kinds, means for ejecting the cast slugs, a guide into which the slugs pass, said guide including a pair of walls, and means for moving one wall relative to the other to a position of maximum separation prior to the time a slug is ejected from the casting means and for thereafter moving said wall 70 75

to a predetermined setting to accommodate the kind of slug cast.

3. In a slug casting machine, the combination of means for casting slugs of different kinds, means for ejecting the cast slugs, a guide into which the slugs pass and including a pair of relatively movable walls, means acting automatically during the ejection of the slug to move one of said walls from a position of maximum separation to a predetermined setting, and means for determining such predetermined setting of the wall.

4. In a slug casting machine, the combination of means for casting slugs of different kinds, means for ejecting the cast slugs, a guide into which the slug passes and including a pair of relatively movable walls, means acting automatically during the ejection of the slug to move one of said walls from a position of maximum separation to a predetermined setting, and means associated with the casting means for determining such predetermined setting of the guide wall.

5. In a slug casting machine, the combination of means for casting slugs of different kinds, means for ejecting the cast slugs, a guide into which the slug passes, said guide including a fixed wall and a movable wall, a slide on which the movable wall is carried, means for adjusting the slide to effect maximum separation of the guide walls prior to the ejection of the slug, means for holding the slide in such position of adjustment, means for releasing the slide upon ejection of the slug, and devices associated with the casting means and with the slide and cooperating to arrest the slide in a predetermined position and thereby effect the proper spacing of the guide wall members for the kind of slug cast.

6. In a slug casting machine, the combination of means for casting slugs of different kinds, means for ejecting the cast slugs, a chute leading to a galley in which the slugs are stacked, said chute being provided with a movable side wall adjustable to different predetermined positions to accommodate the different kinds of slugs, and means carried by the casting means for determining such different positions.

7. In a slug casting machine, the combination of means for casting slugs of different kinds, means for ejecting the cast slugs, a chute leading to a galley in which the slugs are stacked, said chute being provided with a movable side wall adjustable to different predetermined positions to accommodate the different kinds of slugs, and means including a plate fixed on the casting means for determining the position of the movable side wall, said plate varying in size according to the kind of slug cast.

8. In a slug casting machine adapted to cast slugs of different kinds as for instance those with overhanging faces and those devoid of overhanging faces, the combination of means wherein the slugs are cast, slug ejector means, a chute for guiding the ejected slugs to a galley wherein the slugs are stacked, said chute including relatively movable side walls, and means for adjusting the side walls to accommodate the different kinds of slugs, said walls being adapted when slugs with overhanging faces are cast to be positioned beneath such overhanging faces whereby to permit them to be delivered in an upright position to the galley.

9. In a slug casting machine, the combination of means for casting slugs of different kinds, means for ejecting the cast slugs, a chute lead-

ing to a galley wherein the slugs are stacked, said chute being equipped with relatively movable walls adjustable to accommodate the different kinds of slugs, and a buffer plate yieldingly held against the slug during the ejection thereof from the casting means and adapted accurately to locate the slug for delivery into the chute.

10. In a slug casting machine, the combination of means for casting slugs of different kinds, means for ejecting the cast slugs, a chute leading to a galley wherein the slugs are stacked, said chute being equipped with relatively movable walls adjustable to accommodate the different kinds of slugs, means for effecting maximum separation of the walls prior to the ejection of the slug, and means including a buffer plate positionable to hold the walls in their positions of maximum separation, said buffer plate being yieldingly held against the slug during the ejection thereof and adapted as the slug is ejected to allow the walls to assume a predetermined adjustment depending upon the kind of slug cast, and means for effecting such predetermined adjustment of the chute walls.

11. In a slug casting machine, the combination of means for casting slugs of different kinds, means for ejecting the cast slugs, a chute leading to a galley wherein the slugs are stacked, said chute being equipped with relatively movable walls adjustable to accommodate the different kinds of slugs, means for effecting maximum separation of the walls prior to the ejection of a slug, a buffer plate normally held in spaced relation with respect to the casting means but adapted to be released as the maximum separation of the chute walls is effected and actuated to a position nearer the mold wherein the buffer plate cooperates to maintain the walls in their positions of maximum separation, said buffer plate being yieldingly held against the slug and movable thereby to normal position as the slug is ejected, and during such movement to allow the walls to assume a predetermined adjustment depending upon the kind of slug cast, and means for effecting such predetermined adjustment of the chute walls.

12. In a slug casting machine, the combination of means for casting slugs of different kinds, means for ejecting the cast slugs, a chute leading to a galley wherein the slugs are stacked, said chute including a fixed side wall and a movable side wall, a buffer plate, two independently movable slides, one supporting the buffer plate and the other the movable side wall of the chute, means for locking the buffer plate supporting slide in a normal position away from the casting means, means for actuating the other slide to effect maximum separation of the movable side wall and the fixed side wall, means operated by said slide to effect the release of the buffer plate supporting slide, means for moving the latter slide to position the buffer plate nearer the mold and in a position to lock the chute wall supporting slide in a position wherein the walls have their maximum degree of separation, and for yieldingly holding the buffer plate against the slug during the ejection thereof, said buffer plate during the ejection of the slug acting to release the chute wall supporting slide to allow the same to assume a predetermined adjustment depending upon the kind of slug cast, and means for effecting such predetermined adjustment of the slide.

13. A combination according to claim 12, char-

acterized by the fact that the movement of the chute wall supporting slide to its predetermined position of adjustment operates the buffer plate slide lock to allow the same to lock said slide in 5 normal position after the ejection of the slug.

14. A combination according to claim 12, characterized by the fact that the chute wall supporting slide is positively actuated to the position wherein the chute side walls have their 10 maximum degree of separation by a periodically moving portion of the machine, and impositively returned to its predetermined position of adjustment.

15. A combination according to claim 12, characterized by the fact that the different positions of adjustment of the chute wall supporting slide are determined by means associated with the 15 mold.

16. A combination according to claim 12, characterized by the fact that the chute wall supporting slide is actuated to the position wherein the walls have their maximum degree of separation by the line transporter.

17. A combination according to claim 10, characterized by the fact that safety devices are provided for stopping the operation of the machine in the event the buffer plate is not located in position to hold the chute side walls in their positions of maximum separation prior to the ejection of the 30 slug from the mold.

18. In a slug casting machine, the combination of means for casting slugs of different kinds, means for ejecting the cast slugs, a chute for delivering the slugs to a galley wherein the slugs

are stacked, and means engageable with the faces of the slugs during ejection for locating them properly for entry into the chute, said chute being equipped with relatively movable side walls settable automatically to guide the 5 slugs of different kinds to the galley.

19. In a slug casting machine, the combination of means for casting slugs with overhanging faces and those devoid of overhanging faces, means for ejecting the cast slugs, a chute for 10 delivering the slugs to a galley wherein the slugs are stacked and means engageable with the faces of the slugs during ejection for locating them properly for entry into the chute, said chute being equipped with relatively movable side walls positionable, in the case of slugs with overhanging faces, beneath said overhanging faces and in the case of slugs devoid of overhanging faces 15 sufficiently apart to accommodate the full width of the slug.

20. In a slug casting machine, the combination of means for casting slugs of different kinds, means for ejecting the cast slugs, a chute equipped with relatively movable side walls for 20 delivering the slugs to a galley wherein the slugs are stacked, means engageable with the faces of the slugs during ejection for locating them properly for entry into the chute, and devices acting under the control of said means for regulating 25 the spacing of the side walls according to the kind of slug cast.
